ELWIN GUNDLACH INVENTOR

By Victor J. Evans

ATTORNEY

UNITED STATES PATENT OFFICE.

ALWIN GUNDLACH, OF CHICAGO, ILLINOIS.

BOX.

Application filed February 26, 1923. Serial No. 621,408.

To all whom it may concern:

Be it known that I, ALWIN GUNDLACH, a citizen of the United States, residing at Chicago, in the county of Cook and State 5 of Illinois, have invented new and useful Improvements in Boxes, of which the following is a specification.

This invention relates to boxes or crates, and an object of the invention is to provide a box or crate as specified which is light in weight in comparison with approved types of corresponding boxes or crates now on the market, and one which will result in a very material saving in lumber thereby not 15 only decreasing the cost of manufacture of the boxes or crates but assisting in the preservation of the forest.

Another object of this invention is to provide a box or crate as specified which is substantially air tight, and is consequently dust proof, eliminating the necessity of wrapping in paper the articles to be shipped in the boxes, said substantially air and dust proof construction being provided by the 25 novel construction of the box and the manner in which the various meeting portions of the box at its corners overlap in such manner as not only to render the interior of the box dust proof but to increase the 30 strength of the box and provide a strong, durable box of comparatively light weight.

Other objects of the invention will appear in the following detailed description taken in connection with the accompanying 35 drawings wherein:—

Fig. 1 is a perspective view of the improved box.

Fig. 2 is an enlarged fragmentary end elevation of the box showing the construction at one corner.

Fig. 3 is an enlarged fragmentary end elevation of the box showing the construction at a corner other than that shown in Fig. 2.

Fig. 4 is a vertical section through the box.

Fig. 5 is a detail horizontal section taken on the line 5—5 of Fig. 1.

Fig. 6 is a detail vertical section taken 50 on the line 6—6 of Fig. 1.

Fig. 7 is a detail horizontal section taken on the line 7—7 of Fig. 1.

Fig. 8 is a side elevation of one end of the box.

Fig. 9 is an elevation of the back of the 55 box.

Fig. 10 is a plan of the top of the box.

Fig. 11 is an elevation of the upper front.

Fig. 12 is an elevation of the lower front 60 of the box.

Fig. 13 is a plan view of the bottom of the box.

Referring more particularly to the drawings, the improved box which as illustrated is designed for use in shipping pianos, is 65 made up of a back, bottom, top, ends and front sides upper and lower, as shown in Figs. 8 to 13 of the drawings, which sections are made in knocked down or unassembled manner, for shipment of the boxes, and 70 which sections are made so as to properly fit with the other sections in forming a box.

One of the principal features of the present invention is the eliminating of the major portion of wood necessary for the construction of piano or large boxes without detracting from the strength of the box and at the same time reducing the weight of the box so as to save the shipper a considerable amount on freight costs. 80

The back 1 of the box is rectangular in shape and is made up of a plurality of vertical strips 2 spaced relative to each other, and a plurality of horizontal strips 3 which are laterally spaced and which provide rectangular openings in the back structure, as clearly shown in Figs. 4 and 9 of the drawings. By particular reference to Fig. 9 of the drawings it will be noted that the upper and lowermost cross strips 3 are spaced 90 inwardly from the ends of the vertical strips 2 and also that the ends of the horizontal strips 3 are positioned inwardly of the outermost edges of the end vertical strips 2. These particular arrangements are 95 provided to permit overlapping of the ends and edges of the back 1 with the top 4, bottom 5 and ends 6 of the crate structure. The cross strips 3 have a layer of fiber board or analogous material as shown 100 at 7 attached to their inner edges and closing the rectangular openings formed in the back 1.

The bottom 5 of the box is built up similar to the back 1, that is it comprises a 105 plurality of longitudinally extending bracing boards 8 and transverse boards 9 to the inner surfaces of which a layer 10 of

fiber board or analogous material is attached. The longitudinally extending boards 8 project beyond the endmost transverse boards 9, as clearly shown in Fig. 13 of the drawings and they also form skids to facilitate the moving of the boxes when loaded. The bottom 5 fits snugly within the space between the back structure 1, lower front 11 and the ends 6, as clearly shown in Fig. 4 of the drawings. The lowermost transverse strip 3 in the back structure 1 rests upon the inner surface of the fiber board 10 of the bottom structure while the ends of the vertical boards 2 of the back structure overlap the side edge of the bottom 5 to which they are nailed.

The lower front 11 of the box is not of such rigid heavily braced structure and it comprises a plurality of spaced longitudinally extending strips 12 which are connected at their ends by transversely extending strips 13 which assume a vertical position when the box structure is assembled. The upper front 14 is constructed similarly to the lower front 11 in that it comprises a plurality of strips 15, which have their ends connected by transverse strips 17. By particular reference to Fig. 3 of the drawings it will be noted that the edge of the lowermost strip 16 is beveled as shown at 18 so as to fit tightly against the upper edge of the uppermost strip 12. The joint thus formed is overlapped by the cross board 19 of the end structure 6, as clearly shown in Figs. 1 and 3 of the drawings. The upper edge of the uppermost strip 16 is also beveled as shown at 20 and the strip or board 21 along the front edge of the top 4 overlaps the upper beveled edge 20 of the uppermost strip 16, as clearly shown in Fig. 2 of the drawings. The outer edge 22 of the strip 21 is beveled to lie flush with the angle of the upper front 14. It is to be understood that the lower front 11, upper front 14 and top 4 all have a lining of fiber board or analogous material as shown at 23, which linings meet tightly at their joints and overlap so as to provide a dust proof interior for the box.

The ends 6 comprise vertical strips or boards 24, 25 and 26, a diagonal up-right 27, the cross boards 19 and the top and bottom boards 28 and 29 respectively. The top boards 28 have lips 30 formed thereon which overlap the upper edge portion of the upper front 14 at its ends, as clearly shown in Fig. 2 of the drawings and serve as nailing projections to permit the nailing of the upper front 14 to the ends 6. The top cross boards 28 also serves as a nailing board to permit the nailing of the top 4 to the ends, by means of nails 32, as shown in Fig. 6 of the drawings. The bottom boards 19 of the end structures project beyond the up-rights 24 and 26 and overlap the ends of the lowermost strip 12 and lowermost strip 3 of the

lower front and back structures respectively, permitting secure nailing of these members together as shown in Fig. 5 of the drawings and permitting overlapping joints at the meeting portions.

As previously stated the ends of the boards 19 overlap the joints of the upper and lower fronts 14 and 11 respectively at the end portions of these joints and serve to permit nailing as shown at 33.

As clearly shown in the sectional views Figs. 5, 6 and 7 of the drawings the nailing arrangement of the box is such that the nails at the corners in the meeting members extend transversely to each other providing a crossing of the nails to further brace and strengthen the box structure.

It is, of course, to be understood that the invention may be constructed in other manners and the parts associated in different relations and, therefore, I do not desire to be limited in any manner except as set forth in the claims hereunto appended.

Having thus described my invention what I claim is:—

1. A box comprising a back, bottom, top, upper and lower fronts and ends, said ends overlapping the ends of the various other parts of the box and secured directly thereto, and all of the joints of the box overlapping and fitting snugly to provide a dust proof box, said bottom, back, upper and lower fronts, ends and top each composed of a plurality of spaced boards attached to form the respective portions of the box, and linings of relatively thin material attached to the inner surfaces of a part of the box.

2. In a box, a front comprising a lower front and an upper front disposed at an acute angle thereto, the lower edge of said upper front being beveled to tightly fit the upper edge of the lower front, and ends for the box comprising transverse strips having their end portions projecting over and overlapping the ends of the engaging edges of the upper and lower fronts and secured directly thereto, said front composed of a plurality of spaced wooden strips, and a lining of relatively thin rigid material.

3. In a box, a front comprising a lower front and an upper front disposed at an acute angle thereto, the lower edge of said upper front being beveled to tightly fit the upper edge of the lower front, and ends for the box comprising transverse strips having their end portions projecting over and overlapping the ends of the engaging edges of the upper and lower fronts, a top comprising longitudinally extending side boards and transverse end boards, the forward longitudinally extending side board being projected beyond the normal edge of the top for resting upon the upper edge of the upper front.

4. In a box, a front comprising a lower

front and an upper front disposed at an acute angle thereto, the lower edge of said upper front being beveled to tightly fit the upper edge of the lower front, and ends for 5 the box comprising transverse strips having their end portions projecting over and overlapping the ends of the engaging edges of the upper and lower fronts and secured directly thereto, a top comprising longitudinally extending side boards and transverse

end boards, the forward longitudinally extending side board being projected beyond the normal edge of the top for resting upon the upper edge of the upper front, a top cross strip on said ends, and lips formed on 15 said cross top strip and overlapping the upper end boards of the upper front and being nailed thereto.

In testimony whereof I affix my signature.

ALWIN GUNDLACH.
